UNITED STATES PATENT OFFICE.

HERMAN F. POTTER, OF PHILADELPHIA, PENNSYLVANIA.

DESIGN FOR A SIDEBOARD.

SPECIFICATION forming part of Design No. 24,151, dated March 26, 1895.

Application filed October 30, 1894. Serial No. 527,487. Term of patent 7 years.

To all whom it may concern:

Be it known that I, HERMAN F. POTTER, a citizen of the United States, residing in the city and county of Philadelphia, State of Pennsylvania, have invented and produced a new and original Design for a Sideboard, of which the following is a specification, reference being had to the accompanying drawing.

The leading feature of my design for a side-board, is a sideboard having the following described ornamentations: first, the representation of mirror panels, with columns aside of the same; second, representations of coats-of-arms; next, a clock within the representation of a coat-of-arms on the cap of the side-board, and, finally, representations of busts.

In the drawing which represents a portion of the front of a side board: A designates mirror panels, aside of which are columns B.

C designates the central portion of the cap of the side-board, the same being raised above the side portions D. On said portions C and D are moldings E, F, and on the face of the side-board are representations of coats-of-arms G, G', and representations of busts H, which latter may be inclosed in medallions or frames J.

K designates a clock on the cap of the side-board, the same being within the coat-of-arms G.

What I claim is—

The design for a side-board, having thereon the ornamentations substantially as described and shown.

HERMAN F. POTTER.
